CLAIM

The ornamental design for a drum tension rod lock, as shown and described.

DESCRIPTION

FIG. 1 is a top, rear, and right side perspective view of a first embodiment of a drum tension rod lock of our design; FIG. 2 is a top, front, and right side perspective view thereof; FIG. 3 is a top view thereof; FIG. 4 is a bottom view thereof; FIG. 5 is a left side view thereof; FIG. 6 is a right side view thereof; FIG. 7 is a rear view thereof; FIG. 8 is a front view thereof; FIG. 9 is a top, rear, and right side perspective view thereof, shown in an example environment of use on a drum; FIG. 10 is a bottom, rear, and right side perspective view thereof, shown in an example environment of use on a drum; and
FIG. 11 is a top, rear, and left side perspective view thereof, shown in an example environment of use on a drum.
FIG. 12 is a top, rear, and right side perspective view of a second embodiment of a drum tension rod lock of our design;
FIG. 13 is a top, front, and right side perspective view thereof;
FIG. 14 is a top view thereof;
FIG. 15 is a bottom view thereof;
FIG. 16 is a left side view thereof;
FIG. 17 is a right side view thereof;
FIG. 18 is a rear view thereof; and
FIG. 19 is a front view thereof.
FIG. 20 is a top, rear, and right side perspective view of a third embodiment of a drum tension rod lock of our design;
FIG. 21 is a top, front, and right side perspective view thereof;
FIG. 22 is a top view thereof;
FIG. 23 is a bottom view thereof;
FIG. 24 is a left side view thereof;
FIG. 25 is a right side view thereof;
FIG. 26 is a rear view thereof; and,
FIG. 27 is a front view thereof.
FIGS. 9-12 illustrate perspective views of the drum tension rod lock of FIGS. 1-8 and 13-27 in example environments of use on a drum.
The evenly spaced broken lines represent the portions of the design that form no part of the claim. The dot-dashed lines (Continued)

indicate the boundaries of the environmental subject matter and form no part of the claim.
